*Primary Examiner—Louis S. Zarfas**Attorney, Agent, or Firm—Sterne, Kessler, Goldstein and Fox***[57] CLAIM**

The ornamental design for an element of athletic equipment, as shown and described.

DESCRIPTION

FIG. 1 is a left side elevational view of an element of athletic equipment showing my new design;

FIG. 2 is a right side elevational view thereof;

FIG. 3 is a top plan view thereof; and,

FIG. 4 is a rear elevational view thereof.

The broken line showing of a piece of athletic equipment in the figures is environmental only and forms no part of the claimed design.

FIG. 1

FIG. 2

FIG. 3

FIG. 4
